UNITED STATES PATENT OFFICE.

WILLIAM J. WISE AND THOMAS O. ADAMS, OF NEW PHILADELPHIA, OHIO, ASSIGNEES
TO THE WISE-McCLUNG MANUFACTURING COMPANY, OF NEW PHILADELPHIA,
OHIO, A CORPORATION OF OHIO.

VACUUM CLEANER.

1,420,172.

Specification of Letters Patent. Patented June 20, 1922.

Application filed August 5, 1921. Serial No. 439,949.

To all whom it may concern:

Be it known that we, WILLIAM J. WISE and THOMAS O. ADAMS, citizens of the United States, both residing at New Philadelphia, in the county of Tuscarawas and State of Ohio, have invented a new and useful Vacuum Cleaner, of which the following is a specification.

This invention relates to vacuum cleaners and more particularly to that type of cleaner in which the motor and fan chamber are mounted upon a horizontal axis, the nozzle being detachably connected to the fan chamber, and the objects of the invention are to provide a simple and easily operated locking device by means of which the nozzle may be easily and quickly attached to or removed from the casing of the cleaner.

The above and other objects may be attained by providing a locking plate upon the fan casing having an outwardly extending annular flange surrounding the inlet opening to the fan chamber, an outwardly disposed slotted flange being provided upon one side of said plate, a slot or recess being provided in the plate diametrically opposite thereto.

A locking ring is provided in the inner end of the nozzle and contains a pair of lugs, one of which is arranged to be inserted into the slotted flange upon the locking plate, the other lug being rearwardly inclined and arranged to be seated in the recess in the locking plate, a locking lever being pivoted upon the locking plate and arranged to be moved into engagement with said inclined lug, securely locking the nozzle in position upon the fan casing.

A preferred embodiment of the invention thus set forth in general terms is illustrated in the accompanying drawings, in which—

Figure 1 is a front elevation of a vacuum cleaner provided with a nozzle lock embodying the invention;

Fig. 2, a side elevation of the same, parts being broken away to show the attachment of the nozzle to the fan casing;

Fig. 3, a plan view of the sweeper;

Fig. 4, an enlarged, sectional view on the line 4—4, Fig. 1;

Fig. 5, a perspective view of the locking plate;

Fig. 6, a perspective view of the locking ring; and

Fig. 7, a perspective view of the locking lever.

Similar numerals of reference indicate corresponding parts throughout the drawings.

The sweeper comprises the usual motor 60 casing 1, and fan casing 2, which are mounted upon the front wheels 3 and the rear wheel 4. The fan chamber is connected in the usual manner to a dust bag 5 and the cleaner is arranged to be moved to and fro upon the floor by means of a handle (not shown), which is attached to the usual pivoted handle bail 6. These parts of the device may be of any usual form.

The fan chamber 7 communicates with the nozzle 8 through the usual inlet aperture 9, the nozzle being provided with the elongated inlet slot 10, which is held in engagement with the floor in the usual manner.

A locking plate 11 is connected to the outer wall of the fan chamber by means of screws or the like passed through the lug 12, and is provided with a central annular opening 13 registering with the inlet opening 9 of the fan chamber, an outwardly disposed, 80 annular flange 14 surrounding said aperture.

The locking plate 11 is provided upon one side with an outturned flange 15 having the slot 16 therethrough, the diametrically opposite side of the plate being enlarged as shown at 17 and provided with the recess or slot 18. The locking lever 19 is pivoted at 20 upon the locking plate 11 and provided with the inclined locking lip 21 and the finger portion 22, by means of which the lever 90 is manipulated.

The locking ring 23 is attached within the inner, annular end 24 of the nozzle 8 as by the rivets 25 and is provided with an annular flange 26 arranged to engage the face of 95 the locking plate 11 when the ring is inserted from the annular flange 14 of the locking plate.

The locking ring is provided with the radial lug 27 which is arranged to be in-

serted into the slot 16 in the locking plate. Diametric to the lug 27 is a lug 28 having the rearwardly inclined portion 29 arranged to be seated in the recess 18 of the locking plate.

When the cleaner is used for cleaning a floor, the nozzle 8 is attached to the fan casing in the manner shown in Figs. 1, 2 and 3, the sweeper being propelled to and fro upon the floor to be cleaned by means of the handle in the usual manner.

When it is desired to operate the different forms of attachments provided for cleaning upholstery, draperies and the like, which are usually mounted upon a flexible hose, the nozzle 8 may be removed and the flexible hose attached directly to the fan chamber.

The locking device described herein, is provided for the purpose of easily and quickly removing the nozzle from the fan casing when it is desired to apply the attachments. At the same time, the locking device is arranged to hold the nozzle firmly clamped upon the fan casing.

25 In placing the nozzle in position upon the fan casing, the lug 27 is first inserted into the slot 16 of the locking plate, the opposite end of the locking ring and nozzle being tilted slightly away from the locking plate. The nozzle is then tilted toward the locking plate, the locking ring 23 being engaged around the flange 14 of the locking plate, the inclined lug 29 being seated in the recess 18 of the locking plate.

30 15 The locking lever 19 is then swung downwardly upon its pivotal point, the inclined lip 21 thereof passing over the inclined lug 29 of the locking ring, clamping the same securely within the recess 18 of the locking plate and locking the nozzle firmly upon the fan casing.

When it is desired to remove the nozzle from the cleaner, it is only necessary to swing the locking lever out of engagement 45 with the lug 29 after which the adjacent edge of the nozzle may be tilted sufficiently to disengage said lug from the recess 18, and at the same time to disengage the locking ring from the flange 14 of the locking plate when the lug 27 may be withdrawn from the slot 16 of the locking plate.

50 It will be evident from the above, that the locking device described herein is simple in construction, and provides for easily and readily removing the nozzle from the fan casing and attaching the same thereto, and is arranged to securely lock the nozzle to the fan casing when it is attached thereto.

We claim:—

60 1. A suction sweeper including a fan casing having an inlet opening, a slotted flange at one side of said opening, said casing having a recess at the opposite side of the inlet opening, a nozzle arranged to register with

said inlet opening, a lug upon the nozzle arranged to engage the slotted flange, an inclined lug upon the nozzle arranged to be seated in the recess and a clamping lever upon the casing arranged to engage the inclined lug to lock the nozzle to the casing. 70

2. A suction sweeper including a fan casing having an inlet opening, an outwardly disposed flange surrounding said inlet opening, a slotted flange at one side thereof, said casing having a recess at the opposite side 75 of the inlet opening, a nozzle arranged to receive said outwardly disposed flange, a lug upon the nozzle arranged to engage the slotted flange, an inclined lug upon the nozzle arranged to be seated in the recess 80 and a clamping lever upon the casing arranged to engage the inclined lug to lock the nozzle to the casing.

3. A suction sweeper including a fan casing having an inlet opening, an outwardly disposed flange surrounding the inlet opening, a slotted flange at one side thereof, said casing having a recess at the opposite side of the inlet opening, a nozzle, a locking ring attached to the outlet end of the nozzle and 90 arranged to receive said outwardly disposed flange, a lug upon the locking ring arranged to engage the slotted flange, an inclined lug upon the locking ring arranged to be seated in the recess and a clamping lever 95 upon the casing arranged to engage the inclined lug to lock the nozzle to the casing.

4. A suction sweeper including a fan casing having an inlet opening, an outwardly disposed flange surrounding the inlet opening, a slotted flange at one side thereof, said casing having a recess at the opposite side of the inlet opening, a nozzle, a locking ring attached to the outlet end of the nozzle and 100 arranged to receive said outwardly disposed flange, a flange upon the locking ring arranged to engage the outer face of the fan casing, a lug upon the locking ring arranged to engage the slotted flange, an inclined lug upon the locking ring arranged to be seated in the recess and a clamping lever upon the 110 casing arranged to engage the inclined lug to lock the nozzle to the casing. 110

5. A suction sweeper including a fan casing having an inlet opening, a locking plate mounted upon the casing and provided with an opening registering with said inlet opening, an outwardly disposed flange upon the locking plate surrounding said opening, a slotted flange upon the locking plate at one side of and spaced from said outwardly disposed flange, said locking plate having a recess at the opposite side of and spaced from the outwardly disposed flange, a nozzle arranged to receive the outwardly disposed flange, a lug upon the nozzle arranged to engage the slotted flange, an inclined lug upon the nozzle arranged to be seated in the 120 125

recess and a clamping lever upon the locking plate arranged to engage the inclined lug to lock the nozzle to the casing.

6. A suction sweeper including a fan casing having an inlet opening, a locking plate mounted upon the casing and provided with an opening registering with said inlet opening, an outwardly disposed flange upon the locking plate surrounding said opening, a slotted flange upon the locking plate at one side of and spaced from said outwardly disposed flange, said locking plate having a recess at the opposite side of and spaced from the outwardly disposed flange, a nozzle, a locking ring attached to the outlet end of the nozzle and arranged to receive the outwardly disposed flange, a lug upon the locking ring arranged to engage the slotted flange, an inclined lug upon the locking ring arranged to be seated in the recess and a clamping lever upon the locking plate arranged to engage the inclined lug to lock the nozzle to the casing.

7. A suction sweeper including a fan casing having an inlet opening, a locking plate

mounted upon the casing and provided with an opening registering with said inlet opening, an outwardly disposed flange upon the locking plate surrounding said opening, a slotted flange upon the locking plate at one side of and spaced from said outwardly disposed flange, said locking plate having a recess at the opposite side of and spaced from the outwardly disposed flange, a nozzle, a locking ring attached to the outlet end of the nozzle, and arranged to receive the outwardly disposed flange, a flange upon the locking ring arranged to engage the outer surface of the locking plate, a lug upon the locking ring arranged to engage the slotted flange, an inclined lug upon the locking ring arranged to be seated in the recess and a clamping lever upon the locking plate arranged to engage the inclined lug to lock the nozzle to the casing.

In testimony that we claim the above, we have hereunto subscribed our names.

WILLIAM J. WISE.
THOMAS O. ADAMS.
